UNITED STATES PATENT OFFICE.

FRANCIS M. LITTLE, OF YOUNGSTOWN, OHIO.

HAIR-CURLING APPLIANCE.

Application filed July 14, 1927. Serial No. 205,652.

My invention relates to hair curling appliances and more particularly to those of the marcelling or permanent waving type.

Briefly stated, the primary object of the invention is to provide a marcelling or permanent waving appliance employing steam or the equivalent as the heating factor.

Another object of the invention is to furnish a marcelling appliance which employs steam or other fluid as the heating factor and which includes a very simple, compact and easily assembled combination of elements for conducting the heated fluid to the hair engaging members, the hair engaging members being separable.

A still further object of the invention resides in the provision of a fluid heated device of this kind wherein the hair engaging elements are supplied with fluid from a single source.

Another object of the invention is to provide a fluid heated device of the character specified which enables new waves to be put in the hair without disturbing such waves or curls as have been previously made and whereby it is possible to obviate necessity of rewaving the entire strand of hair when all that is necessary to do is to wave the portion of the strand which has grown out from the scalp since the last wave was put in.

The foregoing and other objects of the invention are attained by means of a novel combination and arrangement of parts to be hereinafter described and claimed. However for a better understanding of the invention reference should be had to the accompanying drawings forming a part of this specification and which illustrates what is now considered to be a preferred embodiment of the invention. It is to be understood, of course, that the invention is capable of other mechanical expressions wherein the spirit and scope of the subject matter claimed.

In the drawings, wherein the same reference characters designate the same parts in all views.

Figure 1 is a side elevation of an appliance constructed in accordance with my invention;

Figure 2 is a side elevational view partly broken and partly in section,—the same being taken at right angles to Figure 1, and showing the parts in the position which they assume when the device is in use;

Figure 3 is a longitudinal sectional view 55 corresponding to Figure 2 and showing the

hair engaging elements separated for the insertion of a strand of hair, the casing closure being open for this purpose;

Figure 4 is a cross sectional view taken on the line 4—4 of Figure 2;

Figure 5 is a cross sectional view taken on the line 5—5 of Figure 2;

Figure 6 is a top plan view of a portion of the device,—the saddle, so called,—the same being partly broken and partly in section 65 to show the arrangement of ducts for conducting the fluid to the upper hair engaging element;

Figure 7 is a bottom plan view of the element shown in Figure 6 and showing the 70 means for securing the lower hair engaging element to the saddle,—this view illustrating also the means for conducting the fluid from the saddle to the lower hair engaging element;

Figure 8 is a group perspective view of the 75 saddle and associated elements for mounting and manipulating the hair engaging elements,—which latter is shown in fragmentary form in this view; and,

Figure 9 is a detail perspective view, partly 80 broken, of the yoke member which is controlled by one of the handle elements for separating one of the hair engaging blades or elements from the other.

Referring specifically to the drawings and 85 particularly to Figures 2 and 3,—the device is seen to comprehend a barrel-like member 1 having a chamber 2 open at one end and receiving a closure 3. The pipe 4 which receives the steam or other fluid from a suitable 90 source of supply extends through a medial hole in the closure 3 and has its opposite ends threaded, as at 4^a, to extend through the inner end of the barrel 1 and beyond the outer face thereof to take in the internal threads 95 of the cylindrical end of the lower or fixed hair gripping element 5 which cylindrical end portion provides the steam distributing chamber 5^a. Pipe 4 is shown as having a shoulder 4^b bearing against the inner face 100 of the barrel end and it is clear from the showing in the drawing that the pipe 4 serves the function of holding the lower hair gripping member 5 in assembled relationship with the barrel 1.

It is also noted from the drawings that the lower hair engaging member 5 has a longitudinal passage 5^b through which steam flows from the distributing chamber 5^a, as shown in Figure 7. The end of the passage 5^b is 110

closed, but beginning at a point outwardly of the cylindrical portion the hair engaging member 5 has a number of ports communicating therefrom whereby the steam can pass 5 to contact with the hair at either side these ports being designated at 5^a. The shape of the lower hair engaging element 5 will be best understood from Figure 8, wherein the portion outwardly of the chambered end 5^a is 10 trough-like in contour and tapers gradually to reduced cross section toward the edge opposite that through which the passage 5^b extends. Figure 8 is believed to clearly illustrate how the steam passes from the passage 15 5^b to the ports 5^c.

Mounted upon the chambered end 5^a of the lower hair engaging member 5 is the saddle-like member 6, the central longitudinal bore 6^a of which receives the cylindrical end portion 20 of the member 5 with a snug fit. However, in order to secure the saddle in place I employ the screw 6^b which extends through the bottom of the saddle and into the wall of the cylindrical end of member 5. This screw 25 6^b is to effectually hold the saddle in place and to prevent it from rotating.

The saddle 6 has two main functions,—namely to pivotally mount the upper hair engaging member,—and secondly to serve as 30 the means for supplying the upper hair engaging member with the heated fluid of the distributing chamber 5^a in the end of the member 5.

Figure 6 shows that the saddle 6 has provided adjacent its top longitudinal passages 6^e at either side, the inner ends of which passages may be closed by any suitable means such as machine screws 6^c. Diagonal ducts 5^d communicate from the steam distributing 40 chamber 5^a inwardly of the end of such chamber, with aligned ducts 6^a in the saddle 6 which lead into the passages 6^e. The outer ends of the side passages 6^e of the saddle open into the bearing apertures of spaced 45 ears 6^e at the outer end of the saddle and communicate with the aligned arcual slots 7^a in the pintles 7 of the block 8. The pintles 7 in reality are defined by a tube extending through the block 8 and which is closed at 50 its ends so as to prevent the escape of steam.

The block 8 is formed with an apertured upstanding lug 8^a designed to be embraced by the forked end 10^a of a socket member 10,—a pin 9 insertible through lugs 8^a and the forked end 10^a of socket member 10 serving to pivotally connect the two.

The block 8 is therefore journaled in bearing ears 6^e for vertical swinging movement to be controlled by the threaded rod 11 which 60 is carried by the socket member 10. The operating means for the rod 11 will be referred to more in detail later on and the thing which must be borne in mind at this time is that the arcual slots in the pintles 7 are so arranged 65 to conduct steam inwardly toward the center

of the block from the side passages 6^e of the saddle. The pintles have rather a snug fit in the bearing gears 6^c and accordingly there will be no waste of steam.

Turning now to Figures 3 and 4 it will be clearly evident that the pintle 2 has a central aperture 7^b which communicates with the tubular extension 8^b of the block 8 which is threaded to receive the internally threaded end of the upper hair engaging member, 75 which is of tubular form and closed at its outer end,—there being ports 12^a communicating outwardly through the lower half of said member so as to subject the locks of hair, which are confined between the members 5 and 12 to the action of steam from both of said members at the same time so as to secure the maximum in the way of curling results.

The device includes a pair of handles generally designated at 13, 14 and which are designed to be gripped by the operator to support the appliance when being used. The handle 13 comprehends a sleeve portion 13^a mounted upon a rod 13^b the end of which is screwed into the bearing 13^c which is fastened to the outer wall of the barrel 1, as shown. The handle 14 also includes a sleeve, as shown at 14^a, which is likewise mounted upon a rod 14^b. However, the rod 14^b is screwed into the laterally or rather rearwardly turned socket portion 15^a of a yoke member 15 which is inserted through a slot 1^b in the barrel 1 and is mounted for limited longitudinal swinging movement in the chamber 2 by means of a pivot pin 16 extending through 100 bearings 17, which are secured to the barrel as indicated in Figure 5. Of course, the slot 1^b through which the yoke 15 extends will necessarily be of sufficient length to allow for the necessary movement of the yoke.

This yoke 15 is the member which operates or controls the movement of the rod 11 which is connected to the upper hair engaging member 12 through the block 8. The end of the rod 11 is formed with a slightly enlarged ball portion 11^a which is freely insertible in the intermediate enlarged portion 15^c of a transverse slot 15^b opening from the outer side of the remote end of the yoke 15. The formation of the yoke will be best understood from Figure 9. Here it is advisable to point out that as shown in Figure 3 it is impossible to disengage the spherical end 11^a from the slot 15^b, 15^c without first disengaging the pivot 10, 16. It is perfectly plain from the drawings that the clearance allowed between the outer face of the yoke and the adjacent wall of the chamber 2 is not sufficient to permit disengagement of the part 11^a from its seat. The connection of the rod 11 to the yoke 15 is of a 110 substantially universal character so that when the handle 14 is manipulated the rod 11 will be moved lengthwise through its guide hole 1^c in the end of barrel 1 to manipulate the upper hair curling member 12. The forma- 120

tion of the yoke 15 is such as to clear the steam inlet pipe 4, the bight portion of the yoke passing around the steam inlet pipe 4 with sufficient clearance to permit ready manipulation of the yoke.

The rod 11 has a nut 11^b fixedly secured thereof so that the threaded end can be readily screwed into the socket member 10. Of course, the spherical end 11^a permits free rotation of the rod so that it can be screwed into or out of socket member 10 without necessitating its being disconnected from the yoke 15.

In carrying out the invention the strand or portion of a strand of hair which is to be curled is engaged between the members 12 and 5 and thereupon the barrel 1 is given a twist of about 360 degrees to wind the hair around the members 5, 12. A sectional ring 18, the inner periphery of which is tapered from both sides, engages in a groove 1^d of the barrel 1 and serves to rotatably mount thereon the cylindrical casing 20 which encloses the barrel 6 and the hair engaging members 5, 12 along with the operating rod 11 and associated elements. The purpose of the casing 20 is to prevent the escape of steam and to concentrate the same upon the hair in addition avoiding the necessity of subjecting the customer to undue heat.

The casing 20 comprises an outer shell 21 of bakelite or similar material and an inner shell 23 of steel or other metal. Interposed between the two shells 21, 23 is a layer of asbestos 22 or other insulating material the object of which is to prevent the outer shell 21 from getting hot. The casing 20 is cut away to provide a relatively deep opening 24, as clearly shown in the drawings, and this is adapted to be closed by means of a closure 25 which is hingedly mounted upon the casing, as indicated at 26,—there being a finger knob 27 and a latch member 28 as shown. The closure 25, as clearly illustrated in Figure 4, is constructed similarly to the casing.

In order that the strands of hair may extend outwardly between the closure 25 and the wall of opening 24 without permitting the escape of steam and also without injuring the hair, I provide the opposite edges of the opening 24 with felt strips 29, which are adapted to partake of limited transverse sliding movement between the shell walls 21, 23,—there being slots in the strips 29 to receive retaining screws 30 for limiting the movement of the strips. The strips 29 are backed by springs 31 which bear thereagainst and tend to urge the felt strips into engagement with the asbestos between the steel and bakelite shell portions of the closure 25. The inner ends of the springs, of course, bear against the asbestos intermediate layer of the casing which affords sufficient purchase to cause the springs to urge the strips to the position shown in Figure 4 when the closure 63 is locked down.

The housing 20, at its rear end, has an inward circumferential ridge 32 to engage the V-shaped circumferential groove in the back of ring 18 so as to effect a substantial seal to prevent the loss of steam and the ring 18 is held in place by means of screws 33 as shown.

Figures 2, 3 and 5 show the steam exhaust pipe 34 leading through the inner end of barrel 1, chamber 2 and chamber closure 3. The exhaust pipe 34 can be connected by suitable tubing to any desired point remote from the place of operation of the appliance as for instance to the boiler for reheating.

From the foregoing description read in connection with the accompanying drawings it is believed that the construction and advantages of the invention will be readily understood and appreciated by those skilled in the art. For instance when it is desired to insert a wave in merely one lock or portion of a lock of hair for instance close to the scalp, it is unnecessary to steam or treat the whole strand or lock of hair as is customary with other types of apparatus. The hair to be curled is, of course, thoroughly washed before the device is applied and may also be treated with certain fluids before the waving operation is begun, but inasmuch as such preliminary treatment is old and well known it is not necessary to mention same in detail here.

Having thus described my invention, what I claim as new and desire to secure by Letters Patent is:

1. A device of the class described comprising a pair of hair engaging members, one of said hair engaging members having a fluid conduit provided with an outlet, means for supplying a fluid heating means to said conduit, and a casing for enclosing said hair engaging members.

2. A device of the class described comprising a pair of hair engaging members, said hair engaging members having passages therein and ports leading from said passages, and means for introducing fluid through said passages.

3. A device of the class described comprising a body portion, cooperating fixed and movable hair engaging members having fluid passageways therein, a fluid inlet pipe extending through said body portion and threaded through one end thereof to engage said fixed hair engaging member to hold the same assembled with said body portion, and means for supplying fluid to the passages of said members.

4. A device of the class described comprising a body portion, cooperating fixed and movable hair engaging members having fluid passageways therein, a fluid inlet pipe extending through said body portion and threaded through one end thereof to engage said fixed hair engaging member to hold the same assembled with said body portion, and said

fixed hair engaging member having means for supplying fluid to said movable hair engaging member.

5. A device of the class described comprising cooperating fixed and movable hair engaging members, said fixed hair engaging member having a fluid chamber therein and said movable hair engaging member having a longitudinal passageway provided with restricted transverse outlet means there along, means associated with said fixed hair engaging member for pivotally mounting the movable hair engaging member thereon, and said pivot means having a duct communicating with said fluid chamber and passageway.

6. A device of the class described comprising a body portion, cooperating fixed and movable hair engaging members, having fluid passageways therein, a fluid inlet pipe extending through said body portion and threaded through one end thereof, said fixed hair engaging member having a chambered end with which its fluid passageway communicates, the threaded end of said inlet pipe engaging internal threads in said chamber whereby to hold said fixed member and body portion connected, means for pivotally mounting said movable hair engaging member upon said fixed hair engaging member, and said mounting means having fluid passageways communicating with the fluid passageway of said movable hair engaging member, and said hair engaging members having transverse ports communicating with the fluid passageways thereof.

7. A device of the class described comprising a body portion, cooperating fixed and movable hair engaging members having fluid passageways therein, a fluid inlet pipe communicating through said body portion and threaded through one end thereof, said fixed hair engaging member having a chambered end into which said fluid inlet pipe is threaded to attach the same to said body portion, a saddle detachably secured to said fixed hair engaging member and to which said other hair engaging member is pivoted, the chambered end of said fixed hair engaging member having a fluid passageway communicating with the fluid passageway of said fixed hair engaging member, said saddle having a fluid passageway communicating with said movable hair engaging member through its pivot point and communicating with the chambered end of said fixed hair engaging member, and means for actuating said movable hair engaging member to effective engagement with said fixed hair engaging member.

8. A device of the class described comprising a movable hair engaging member having a fluid passageway, a fixed hair engaging member having a fluid inlet chamber and a passageway communicating therefrom, said fixed hair engaging member having a second

fluid passageway leading from said chamber, means including a pivot pin for pivotally mounting said movable hair engaging member upon said fixed hair engaging member, said pivot pin being hollow and communicating with the second mentioned passageway of said fixed hair engaging member and with the fluid passageway of said movable hair engaging member.

9. A hair curling device comprising a chambered body portion, cooperating fixed and movable hair engaging members, a fluid inlet pipe extending through said chambered body portion and threaded through one end thereof, said fixed hair engaging member having a chambered end into which the end of said pipe is threaded whereby to support said fixed hair engaging member upon said body portion, said fixed hair engaging member having a longitudinal passageway communicating with the chambered end of said member, a saddle detachably secured upon the end of said fixed hair engaging member adjacent said body portion, opposed ears at one end of said saddle, said saddle having passageways communicating with the chambered end of said fixed hair engaging member, a hollow pin closed at its ends and journaled in said saddle ears and through the end of said movable hair engaging member for pivotally mounting the same upon said saddle and said fixed hair engaging member, the passageways of said saddle communicating with the interior of said pivot pin and the movable hair engaging member having a passageway communicating with the interior of said pivot pin whereby fluid can pass from the chambered end of said fixed hair engaging member through said saddle passageways and pivot pin into the passageway of said movable hair engaging member, operating means secured to said movable hair engaging member, a handle movably mounted upon said body portion and having a portion extending into the chamber of said body portion and engaging said operating member therein whereby said movable hair engaging member can be actuated to and from cooperative engagement with said fixed hair engaging member.

10. A device of the class described comprising a body portion having a fluid chamber having a fluid inlet, cooperating fixed and movable hair engaging members, one of said members having a longitudinal passageway communicating with said chamber, said passageway having transverse ports leading therefrom, and operating means for said movable hair engaging member.

11. A device of the class described comprising a body portion, a fixed hair engaging member supported thereby and having a fluid inlet chamber and a longitudinal passageway communicating with said chamber, a second hair engaging member pivotally mounted upon said first hair engaging member and

having a longitudinal fluid passageway therethrough, said fixed hair engaging member having means to supply the fluid from its chamber to the passageway of said pivoted 5 hair engaging member, each of said hair engaging members having transverse ports communicating with their fluid passageways to permit the fluid to escape therefrom, a closure removably carried by said body portion, and 10 a fluid outlet pipe associated with said closure.

12. A device of the class described comprising a body portion, a fixed hair engaging member supported thereby and having a fluid inlet chamber and a longitudinal passageway 15 communicating with said chamber, a second hair engaging member pivotally mounted upon said first hair engaging member and having a longitudinal fluid passageway therethrough, said fixed hair engaging member 20 having means to supply the fluid from its chamber to the passageway of said pivoted hair engaging member, each of said hair engaging members having transverse ports communicating with their fluid passageways to 25 permit the fluid to escape therefrom, and a closure removably carried by said body portion.

13. In a device of the class described having a pair of hair engaging elements and a 30 body portion for supporting the same, a housing secured to said body portion and enclosing said hair engaging members, said housing comprising spaced inner and outer shell members, and insulating material disposed 35 between said shell members.

14. In a device of the class described comprising a body portion, and a pair of hair engaging members carried by said body portion, an insulated housing open at one end and 40 insertible over said body portion to enclose said hair engaging members, and attaching means for said housing associated therewith and with said body portion for sealing the open end of said housing.

45 15. In a device of the class described comprising a body portion, and a pair of hair engaging members carried by said body portion, an insulated housing open at one end and insertible over said body portion to enclose said hair engaging members, and attaching means for said housing associated therewith and with said body portion for sealing the open end of said housing, and said housing comprising an inner and outer shell, 50 and insulating material disposed between 55 said shells.

16. In a device of the class described comprising a body portion, and a pair of hair engaging members carried by said body portion, 60 an insulated housing open at one end and insertible over said body portion to enclose said hair engaging members, and attaching means for said housing associated therewith and with said body portion for sealing the open end of said housing comprising

ing inner and outer shells and being cylindrical in form, said housing having a portion of its walls cut away to provide an opening whereby the hair can be engaged with said hair engaging members, a closure for said 70 opening comprising inner and outer spaced plates, insulating material interposed between said plates and terminating short of the side edges thereof to provide a space between said plates, the insulating material between the 75 shells of said housing and adjacent the edges of said opening being spaced from said edges, strips of relatively soft material disposed in said spaces and between the plates of said housing, yielding means for urging said strips 80 beyond the edges of said opening whereby they will be engaged between the plates of said closure when the same is in place so as to prevent injury to the hair extending outwardly of said housing between the edges of said 85 closure and an opening.

17. In a device of the class described comprising a body portion, and a pair of hair engaging members carried by said body portion, an insulating housing open at one end and insertible over said body portion to enclose said hair engaging members, and attaching means for said housing associated therewith and with said body portion for sealing the open end of said housing comprising 90 inner and outer shells and being cylindrical in form, said housing having a portion of its wall cut away to provide an opening whereby the hair can be engaged with said hair engaging members, a closure for said 95 opening comprising inner and outer spaced plates, insulating material interposed between said plates and terminating short of the side edges thereof to provide a space between said plates, the insulating material between the 100 shells of said housing and adjacent the edges of said opening being spaced from said edges, strips of relatively soft material disposed in said spaces and between the plates of said housing, yielding means for urging said strips 105 beyond the edges of said opening whereby they will be engaged between the plates of said closure when the same is in place so as to prevent injury to the hair extending outwardly of said housing between the edges of said 110 closure and said strips having transverse slots, and pins extending through said housing shells and strip slots to secure said strips between the said housing shells for movement under the influence 115 of said spring.

18. In a device of the class described, a chambered body portion, cooperable fixed and movable hair engaging members carried by said body portion, a control element extending from said movable hair engaging member and into the chamber of said body portion, a control handle pivoted to said body portion and having a yoke-like extension extending into said body portion chamber, said 125 130

control element having a spherical end and the yoke portion having a centrally enlarged edge groove to receive said spherical end.

19. A device of the class described comprising a pair of hair engaging members, one of said engaging members having a fluid conduit provided with an outlet, means for supplying a fluid heating means to said conduit, a casing for enclosing said hair engaging members, 10 said casing having an opening, a closure for said opening and the contacting portions of said closure and opening having coating sealing portions of relatively yieldable material.
- 15 20. A device of the class described comprising a pair of hair engaging members, one of said hair engaging members having a fluid conduit provided with an outlet, means for supplying a fluid heating means to said conduit, a casing for enclosing said hair engaging members, said casing having an opening to receive said hair engaging members, and one of said hair engaging members having sealing means cooperating with a portion of 20 said casing for sealing said opening when the members are within the casing.
- 25 21. A device of the class described comprising a pair of hair engaging members, one of said hair engaging members having a fluid conduit provided with an outlet, means for supplying a fluid heating means, to said con-

duit, a casing for enclosing said hair engaging members, said casing having an opening to receive said hair engaging members, one of said hair engaging members having sealing means cooperating with a portion of said casing for sealing said opening when the members are within the casing, said casing having a second opening through which the hair extends, a closure for said second opening and means associated with the contacting portions of said closure and casing for sealing the opening protecting the hair from injury when the closure is closed. 35

22. A device of the class described comprising a pair of hair engaging members, one of said hair engaging members having a fluid conduit provided with an outlet means for supplying a fluid heating means to said conduit, a casing for enclosing said hair engaging members, said casing having an opening to receive said hair engaging members, one of said hair engaging members having sealing means cooperating with a portion of said casing for sealing said opening when the members are within the casing and the sealing means of said hair engaging member having a fluid outlet port communicating with the interior of said casing. 40

In testimony whereof I affix my signature.

FRANCIS M. LITTLE.
